C. RIGBY

GOLF CLUB

Filed Dec. 6, 1926

Fig. 1-

Fig. 3-

Fig. 4-

UNITED STATES PATENT OFFICE.

CHARLES RIGBY, OF CINCINNATI, OHIO.

GOLF CLUB.

Application filed December 6, 1926. Serial No. 152,853.

My invention relates to golf clubs, and has for its object the providing of novel means whereby the golf club may be taken apart for convenience in carrying the same, and whereby a single handle may be arranged to serve for a number of heads, and whereby handles of different lengths may be provided for a given head shaft.

It is the object of my invention to provide the club with a joint in the length of the club, which when connected will secure the two sections in non-rotative and endwise relations without destroying the resiliency of the club.

A further object of my invention is to provide a tubular shaft for a club with fixed collars and plugs and means to assist in dissociating the two sections of the club.

My present invention is an improvement on the invention shown, described and claimed in my copending application for patent on improvements in golf clubs, filed in the United States Patent Office October 7, 1926, Serial No. 140,139.

I have found that one of the important features of a golf club made in sections is that there be a positive lock between the sections to aid in readily assembling the shaft sections and to prohibit relative turning between the shaft sections when the club is in use so as to maintain firmness of the club. In my improved club I form the joint in such manner as to insure a non-rotative relation between the shaft sections, but which can be easily dissociated without the aid of tools. I further provide novel means for separating the sections of the club.

The invention will be further readily understood from the following description and claims, and from the drawings, in which latter:

Fig. 1 is a side elevation of my improved club of standard length.

Fig. 2 is a similar view of the same showing a short handle section.

Fig. 3 is a longitudinal section, taken on the line 3—3 of Fig. 1, partly broken away, showing my preferred joint.

Fig. 4 is a cross section of the same, taken in the plane of the line 4—4 of Fig. 3.

Fig. 5 is a side elevation of a modified form of my invention, partly broken away.

Fig. 6 is a longitudinal section of the same, taken in the plane of the line 6—6 of Fig. 5, partly broken away.

Fig. 7 is a longitudinal axial section of a further modified form of the same, partly broken away.

Fig. 8 is a longitudinal axial section of an additional modified form of the same, partly broken away; and,

Fig. 9 is a cross-section of the same, taken in the plane of the line 9—9 of Fig. 8.

I have shown my invention applied to a club having a tubular steel shaft 21 provided with a head 22 and a handle 23. The shaft is divided at 24, forming an upper handle section 25 and a lower head section 26. In my preferred form, one of the sections, exemplified as the handle section 25, is provided with a plug 27 which is rigidly secured therein, as by brazing. The plug 27 has an extension 28, which forms a tapered shank.

The other section 26 of the shaft has a plug 29 fixed in its upper end, as by being brazed therein. This plug has a tapered bore 30, arranged to receive the tapered shank 28.

The complementary walls of the tapered shank and tapered bore may be provided with a relief portion or portions for aiding in their ready assembly and release. Thus the tapered shank is provided with a taper portion 31 at the body of the plug and a tapered outer end 32. Intermediate of the two tapered portions, the shank is undercut, as at 33.

A shoulder 34 is formed between the body portion of the plug 27 and the tapered extension. I provide the plug with positioning pins 35 located in the shoulder 34. The pins 35 are pressed into holes 36 in the plug.

The plug 29 has holes 38 about its upper end, positioned to receive the pins 35 for maintaining the shaft sections in non-rotative relation when connected.

To the outer portion of the shaft section 25 I fix a collar 40, as by brazing, and to the shaft section 26 I fix a collar 41. A sleeve 42 having an inwardly extending flange 43, forming a shoulder, is received over the collar 41, and has threaded connection 44 with the collar 40, for drawing the shaft sections toward one another, and thereby causing a wedging fit between the tapered portions 31, 32 of the shank and the walls of the bore 30.

This joint being of substantially great length and of slight taper and otherwise of

novel construction, permits a slight creeping between the complementary walls of the tapered shank and tapered bore, the creeping being in opposite directions at opposite sides of said shank, for absorbing the whipping action of the head to prevent detrimental vibration at the handle at the impact between the head and the golf ball, but insuring sufficient rigidity between the sections of the 10 tubular shaft of the club to insure accuracy and distance in the driving of the ball.

A knurled nut 45 is provided with an inwardly extending flange 46, forming a shoulder which coacts with the outer end of the 15 collar 40 and has threaded connection 47 with the sleeve 42, and aids in drawing the collars toward one another, and locks the threaded parts together. The sleeve 42 is also knurled to permit easy turning of the 20 same.

The tubular sections are preferably slightly spaced apart endwise by an annular space 48, when said sections are connected, which aids in absorbing the whipping of the head section 25 of the club. This space is located between the shoulder 34 of the upper section and the end of the lower shaft section. The pins 35 are also preferably spaced from the bottoms of the holes 38.

30 The sections of the club are easily separated for knock-down relation of the club, and to aid in separating the sections I provide a shoulder, shown as a collar 50, fixed to the tubular section 26 and spaced from the 35 sleeve 42. To disconnect the sections the nut 45 is unthreaded and the sleeve 42 rotated. When the sleeve contacts the collar 50 it will force the shaft sections to separate and thereby withdraw the tapered shank 28 from 40 the bore 30.

I have shown the taper shank 28 as extending from the handle section and the tapered bore 30 as located in the head section of the golf-club, but it is obvious that 45 the shank may extend from the head section and the tapered bore be located in the handle section. The sleeve 42 may be located about the handle section and the arrangements of the complementary fastening means 50 and of the locking means may be correspondingly reversed, without departing from the spirit of my invention as embraced in the scope of the appended claims.

In the modified form shown in Figs. 5 and 55 6, I provide a cross pin 55 positioned in the taper shank 31. The ends of the pin 55 are received in slots 56 in the upper end of the lower shaft section for arresting relative rotation between the shaft sections. The pins 60 are preferably spaced from the bottom of the slots 56 when the shaft sections are assembled.

In Fig. 7 I provide the end of the tapered shank 31 adjacent the body portion of the plug 27 with a square portion 60, which is 65 received in a square recess 61 in the plug 29

for contact with the complementary walls of said recess for arresting relative rotation between the shaft sections. The bottom wall of the recess is preferably spaced from the square portion 60 when the parts are in assembled relation.

In the modification shown in Figs. 8 and 9 I provide one of the shaft sections, shown as the handle section, with lengthwise extending projections, shown as lugs 65 extending from the collar 40, which are arranged to be received in corresponding slots 66 in the proximate end of the other shaft section, shown in the collar 41. Engagement between the walls of the lugs and slots arrests 80 relative rotation between the shaft sections. The outer ends of the lugs are preferably spaced from the bottoms of the slots when the parts are assembled.

In my improved device a single handle 85 section may serve a number of head sections, and handle sections of different lengths may be connected with a single head section. Thus a shorter handle section, exemplified at 70, may be connected with a head section, 90 which is admirable, for instance, when putting.

The sections of my improved club may be readily disconnected for being conveniently received in a usual suit case or Gladstone bag, or for other convenient packing, making the carrying of the usual golf bag 95 unnecessary when traveling.

Having thus fully described my invention, what I claim as new, and desire to secure by 10 Letters Patent, is:

1. A golf club comprising a handle section and a head section, means at the proximate ends of said sections securing said sections together comprising a tapered shank 105 extending from one of said sections and received in a tapered bore in the other of said sections forming a wedge connection between said sections, means interposed between said sections for arresting relative 110 rotation between said sections, and a rotatable sleeve received over the adjacent ends of said sections, said sleeve and said sections provided with complementary means respectively for drawing said sections together 115 and for dissociating said tapered shank and the wall of said tapered bore by rotations of said sleeve in opposite directions.

2. A golf club comprising a handle section and a head section, means at the proximate ends of said sections securing said sections together comprising a tapered shank extending from one of said sections and received in a tapered bore in the other of said sections forming a wedge connection between said sections, means between said sections for arresting relative rotation between said sections, a space between said two sections about said shank, and a sleeve received over the adjacent ends of said sections for 120 125 130

closing said space between said sections and clamping said sections together.

3. A golf club comprising a handle section and a head section, means at the proximate ends of said sections securing said sections together comprising a tapered shank extending from one of said sections and received in a tapered bore in the other of said sections forming a wedge connection between said sections, means interposed between said sections for arresting relative rotation between said sections, a sleeve received over the adjacent ends of said sections for drawing said sections together, and a collar on one of said sections complementary to said sleeve for aiding in dissociating said tapered shank and the wall of said tapered bore when disconnecting said sections.

4. A golf club comprising a handle sec-

tion and a head section, means at the proximate ends of said sections securing said sections together comprising a tapered shank extending from one of said sections and received in a tapered bore in the other of said sections forming a wedge connection between said sections, and a sleeve received about the proximate ends of said sections, one of said sections and said sleeve provided with complementary threads for drawing said sections toward one another, and the other of said sections provided with a shoulder with which said sleeve coacts when unthreading said threads to force said sections relatively endwise for release of said wedge connection.

In testimony whereof, I have hereunto signed my name.

CHARLES RIGBY.
